UNITED STATES PATENT OFFICE.

FREDERICK ECKHARD AND CHRISTIAN ECKHARD, OF ST. LOUIS,
MISSOURI.

MOLD FOR MAKING CONCRETE BLOCKS.

SPECIFICATION forming part of Letters Patent No. 790,291, dated May 23, 1905.

Application filed March 7, 1905. Serial No. 248,942.

To all whom it may concern:

Be it known that we, FREDERICK ECKHARD and CHRISTIAN ECKHARD, citizens of the United States, and residents of the city of St. Louis, Missouri, have invented certain new and useful Improvements in Molds for Making Concrete Blocks, of which the following is a specification containing a full, clear, and exact description, reference being had to the accompanying drawings, forming a part hereof.

Our invention relates to molds for making concrete blocks; and it consists of the novel features herein shown, described, and claimed.

The object of our invention is to provide improved mechanism for making concrete blocks, either hollow, solid, or reinforced, of any size, shape, or ornamentation.

The further object is to provide such a machine with improved movable and detachable sides and end plates and an improved handle which will automatically open, close, and lock the sides and end plates during operation.

In the drawings, Figure 1 is a perspective view of a machine embodying our invention. Fig. 2 is a sectional side elevation. Fig. 3 is a perspective view of one of the end plates detached.

1 indicates the side plates, 2 the end plates, and 3 the automatic handles. The side plates are provided adjacent to each of their ends with a pair of inclined cam-slots 4, which terminate at their upper ends in vertical locking-recesses 5. The side pieces 1 are provided with strengthening ribs or flanges 6, as are also the end pieces 2. Said end pieces also have forwardly-projecting shoulders 7, which extend a distance beyond the said flanges or ribs in order to form an additional brace. Near the upper edge of the end pieces are horizontal projecting rods or bolts 8. Additional rods or bolts 9 also project horizontally from the ends of the end pieces at a point beneath the said rods or bolts 8. These rods or bolts 8 and 9 are preferably of sufficient length to pass entirely through the said end pieces. The said rods or bolts 8 and 9 project outwardly through the inclined cam-slots 4 of the said side pieces.

The automatic handles 3 are located at op-

posite ends of the machine and provided at a point adjacent to the outer ends with a series of inclined cam-slots 11, terminating at their upper ends in vertical locking-recesses 12. The series of cam-slots 11 in said automatic handles are provided for the purpose of making concrete blocks of various sizes. Said automatic handles are also provided adjacent to their upper edges with suitable hand-holes 13. Bolts or rods 14 project from the ends of the side plates 1 through the said inclined cam-slots 11.

15 indicates the bottom of the mold, which is made use of in the usual manner.

16 indicates downwardly and outwardly projecting lugs formed upon the side plates 1 at or adjacent to their lower edges, and said lugs are adapted to engage the edge of the bottom 15 and hold the same in position.

The operation is as follows: The usual cores are to be placed in the mold when it is desired to make hollow blocks. The usual combination-core (not shown) is to be used when it is desired to make blocks with horizontal as well as vertical air-spaces. A number of other common appurtenances are to be used in connection with our improved mold; but these need not be described herein, as their construction and uses are well known. The parts of the mold are of course to be assembled as shown in Fig. 1, and then the mold is to be filled with concrete and tamped in the usual manner. When it is desired to remove the block from the mold, the operator grasps the automatic handles 3 by means of hand-holes 13 and pulls the same upwardly. The upward movement of said automatic handles causes the inclined walls of the cam-slots 11 in the automatic handles to engage their rods 14, thereby spreading apart the opposite side plates 1 and separating the same from the concrete block, and as the upward movement of the said automatic handles is continued the said side plates will also be moved upwardly, thereby causing the walls of their inclined cam-slots 4 to engage the bolt or rods 8 and 9 of the end pieces 2 and forcing the said end pieces outwardly away from the concrete block. When the mold is again set down, the parts

assume their normal positions with the bolts or rods 8, 9, and 14 in the locking-recesses at the upper ends of the said inclined cam-slots and said locking-recesses securing the locking parts together until the automatic handles are again elevated. When it is desired to make a narrower concrete block, the bolts or rods 14 are placed in an inner set of the inclined cam-slots 11.

10 What we claim is—

1. A separable mold for making concrete blocks, having movable sides, provided with inclined cam-slots; end pieces provided with rods which engage said inclined cam-slots; and handles having inclined cam-slots for separating said sides from the block contained within the mold; substantially as specified.
- 15

2. A separable mold for making concrete blocks, having movable sides, provided with inclined cam-slots; end pieces provided with rods which engage said inclined cam-slots; rods projecting from the ends of said side pieces; and handles having inclined cam-slots, the walls of which engage the rods of said side pieces; substantially as specified. 25

In testimony whereof we have signed our names to this specification in presence of two subscribing witnesses.

FREDERICK ECKHARD.
CHRISTIAN ECKHARD.
